(57) **CLAIM**

The ornamental design for a wireless amplified speaker system, as shown and described.

DESCRIPTION

FIG. 1 is a front, top, perspective view of a wireless amplified speaker system showing my new design;
FIG. 2 is a front view thereof;
FIG. 3 is a rear view thereof;
FIG. 4 is a top view thereof;
FIG. 5 is a bottom view thereof;
FIG. 6 is a side view thereof, the opposite side view being a mirror image;
FIG. 7 is a cross sectional view along the line 7-7 in FIG. 2; and,
FIG. 8 is a cross sectional view of the section marked by line 8-8 in FIG. 3.
The intersecting broken lines in the Figures show a textured surface or cloth.
The other broken line showing is of environmental material and forms no part of the claimed design.
